R. E. TUPPER.
CURTAIN LIGHT.
APPLICATION FILED NOV. 19, 1918.

1,312,087.

Patented Aug. 5, 1919.

Inventor,
Russell E. Tupper,
By *A. Blipham*,
Attorney.

UNITED STATES PATENT OFFICE.

RUSSELL E. TUPPER, OF COCHITIUTE, MASSACHUSETTS.

CURTAIN-LIGHT.

1,312,087.

Specification of Letters Patent. Patented Aug. 5, 1919.

Application filed November 19, 1918. Serial No. 263,205.

To all whom it may concern:

Be it known that I, RUSSELL E. TUPPER, a citizen of the United States, and a resident of Cochituate, in the county of Middlesex and Commonwealth of Massachusetts, have invented certain new and useful Improvements in Curtain-Lights, of which the following is a clear and exact specification.

The object of this invention is the construction of improved means for renewing injured and broken lights in automobile curtains and the like, whereby the repairing can be done by the owner or chauffeur of the car without sending the curtain away to an expert.

To this end, I provide a thin metallic strip which can be clamped about the edges of a new light and attached to the curtain by projecting spurs and cement.

In the drawings forming part of this specification, Figure 1 is an elevation of a portion of a curtain showing a light attached thereto by my improved means. Fig. 2 is an elevation of parts of the same viewed from within the car. Fig. 3 is a face view of a section of the metal strip before it has been doubled on itself laterally. Fig. 4 is a view of the same after being doubled. Fig. 5 is a perspective view of the same. Fig. 6 is a section on the line 6—6 in Fig. 2. Fig. 7 is a cross section on the line 7—7 in Fig. 5.

Referring to Fig. 2, the reference numeral 1 designates a portion of a curtain having an opening into which a new light 2 of celluloid or the like has been fitted; 3 is a part of the attaching strip, and 4 is the binding which is ordinarily stitched to the curtain and original light about the illuminating opening.

The metal strip 3 has numerous V-shaped notches 5 in its edges, as shown more fully in Fig. 3, to enable it to be conveniently bent to fit a curved outline as shown in Fig. 1. In one edge, pairs of slits 6 are cut about to the bend 7, and the tongues 9 thus formed are sharpened to render their penetration in the fabric composing the binding 4 quite easy. When this metal strip is finally ready to be used, its fingers or spurs 9 are standing at right angles to its plane, as shown in Figs. 5 and 7. Further, numerous indentations 10 have been impressed therein as shown in Fig. 3, to form slight projections 11 as shown in Fig. 7. These projections 11 are for the purpose of engaging the edges of the light 2

when clamped between the two members of the strip 3 and thereby to insure against its withdrawal.

In employing this means for attaching new lights to a curtain, the row of stitches 60 near the edge of the binding 4, by which the damaged light was retained in place, is carefully cut to separate this edge of the binding from the light and the curtain. Then the old sheet of transparent material 65 composing the light is removed, and the new sheet or light 2, cut to proper dimensions and having the strip of sheet metal 3 clamped about its edges, is introduced between the binding 4 and the curtain 1, at the same time 70 pressing the pointed fingers or spurs 9 through the binding and bending these spurs flat down against the surface of the binding, as shown in Figs. 2 and 6.

All that now remains to be done is to cement the inner edges of the binding and curtain to the contacting surfaces of the light, as indicated in Fig. 6, and the operation is completed.

When a light thus inserted becomes itself 80 injured, it is a similarly easy task to run a knife edge between the cemented surfaces, to unbend the spurs 9, remove the light and its clamping strip, pry the jaws of the latter slightly apart to release the damaged light, 85 and to introduce and cement a fresh light in the manner already described.

It is readily seen that this device provides not only a convenient and ready means for replacing old lights with new ones, but for 90 the application in the original manufacture of the curtains, of the lights.

What I claim is:

1. The combination with a fabric having an opening through it and a sheet to be attached over the opening, of a clamping strip composed of sheet metal folded over upon itself along a longitudinal line and inclosing the edges of the said sheet, the clamping strip having pointed projections for engaging said sheet, and pointed tongues for engaging the fabric. 95

2. The combination with a fabric having an opening through it and a sheet to be attached over the opening, of a binding strip 105 stitched to the fabric near its edge spaced from the edge of the opening, and a clamping strip composed of sheet metal folded over upon itself along a longitudinal line and inclosing the edges of the said sheet, 110

the clamping strip having pointed projections for engaging said sheet and pointed tongues for engaging said binding, said strip being disposed between the binding and fabric and cemented therein.

3. The combination with a fabric having an opening through it and a sheet to be attached thereto over said opening, of a clamping strip composed of sheet metal folded over on itself along a longitudinal line and inclosing the edge of said sheet, and a

binding strip stitched and cemented to the fabric about said opening with the clamping strip between, the outline of the opening being partially curved and the clamping strip having numerous notches in its edge to permit its being curved to correspond with the opening. 15

In testimony that I claim the foregoing invention, I have hereunto set my hand this 20 14th day of November, 1918.

RUSSELL E. TUPPER.
